(57) **ABSTRACT**

A weather resistant temporary wall system and method useful for forming a temporary barrier during building construction or renovation includes a series of modular wall panels that may be removably fit together in the size needed. The wall panels have complimentary shaped edge profiles that form a protective barrier against water penetration. The wall panels may be assembled on site in vertically stacked relationship between a pair of support posts which extend from floor to ceiling. The side edges of the wall panels have edge profiles that are complimentary in shape to the side edges of the support posts such that the panels may be removably attached to the support posts. The wall panels may further include a string reinforced polyethylene material for increased strength.

FIG.10

FIG.11

WEATHER RESISTANT TEMPORARY WALL SYSTEM AND METHOD

BACKGROUND OF THE INVENTION

This invention relates to a temporary wall system which provides a protective barrier against inclement weather and is particularly useful in the building construction field.

Building construction and building renovations may expose the interior of the building under construction or renovation to the outside due to the lack of a complete perimeter wall. For example, the façade of many buildings are frequently renovated to maintain their so-called "curb-side appeal". During renovation, the exterior walls are sometimes removed thereby exposing the interior space to the outside. Should there be inclement weather while the exterior walls are removed, the interior space is at risk of damage due to the entry of wind, rain and/or snow, for example. There therefore exists a need for a temporary, weather resistant wall structure which can be easily and quickly erected at a location outwardly of but adjacent the existing exterior wall structure which is about to undergo renovation, and likewise easy and quick to disassemble once renovations are complete.

SUMMARY OF THE INVENTION

The present invention addresses the above needs by providing a weather resistant temporary wall structure system which is easy and quick to both assemble and disassemble. The system includes modular wall panels which include profiles along their side edges to permit them to removably attach to support posts which themselves are secured in place from floor to ceiling. The panels further include edge profiles along their respective top and bottom edges which permit one panel to slidably attach to an adjacent panel located above or below the first panel. The top and bottom edge profiles may be formed with geometries that will impede the entry of rain therebetween.

The panels may be formed of expanded polystyrene (EPS) or other material. The wall panels may further include a reinforcement structure integrated into each panel such as a furring channel, for example. The reinforcement could either be integrated into the panels when the panels are made or could be attached thereafter. A reinforcement structure such as a furring channel, for example, could easily slide into a complimentary shaped channel cut or otherwise formed in the panel, for example. The furring channel or other reinforcement structure can extend perpendicularly relative to the floor-ceiling support posts, or it may extend at other angles if desired. The wall panels may optionally be structurally reinforced with a string reinforced polyethylene applied to one or both of the opposite planar surfaces of the panel.

BRIEF DESCRIPTION OF THE DRAWINGS

The invention will further be described, by way of example, with reference to the accompanying drawings:

FIG. 1 is a perspective view of a temporary wall system in accordance with an embodiment of the present invention;

FIG. 2 is a perspective view of a support post used within the temporary wall system shown in FIG. 1;

FIG. 3 is a perspective view of a first modular wall panel being coupled to the support post shown in FIG. 2;

FIG. 4 is a perspective view of the first modular wall panel of FIG. 3 coupled to the support post;

FIG. 5 is a perspective view of a second modular wall panel being coupled to the first modular wall panel and the support post;

FIG. 5A is a fragmented, enlarged plan view of the adjoining wall panels top and bottom edges in spaced relation to each other;

FIG. 6 is a perspective view of the second modular wall panel of FIG. 5 coupled to the first modular wall panel and the support post;

FIG. 6A is the view of FIG. 5A showing the top and bottom edges in abutting relation to each other;

FIG. 7 is a perspective view of a second support post coupled to the first and second modular wall panels;

FIG. 8 is a perspective view of third and fourth modular wall panels coupled to the second support post;

FIG. 9 is a side perspective view of a panel channel in accordance with an embodiment of the present invention;

FIG. 10 is a perspective view of a furring channel in accordance with an embodiment of the present invention;

FIG. 11 is a modular wall panel including a reinforcing material in accordance with an embodiment of the present invention.

Similar reference characters refer to similar parts throughout the several views of the drawings.

25

DETAILED DESCRIPTION

Referring now to FIGS. 1-8, a weather resistant temporary wall structure system 20 generally includes a plurality of support posts 22 and modular wall panels 24 arranged to form a temporary wall structure 26. Each support post 22 may be adapted to removably attach and extend between a floor 28 and ceiling 30. Each support post 22 may include first and second opposite side edges 32, 34, each having a predetermined edge profile. Each modular wall panel 24 may include opposite outside and inside planar surfaces 38, 40 and top and bottom edges 42, 44 each having a predetermined profile, and opposite first and second side edges 46, 48 each having a predetermined edge profile. The profile of each of the wall panel first and second side edges 46, 48 may be formed complimentary to the profile of each of the support post first and second side edges 32, 34 such that wall panels 24 may be removably attached to and between the support posts.

By way of example and by no means limiting solely thereto, each support post 22 may include a generally U-shaped cross section profile thereby having the first side edge 32 include an edge profile defining a groove 36 and second side edge 34 having a planar edge profile. Alternatively, a support post 22 may include an I-shaped cross section profile having each first and second side edge 32, 34 defining opposing groove edge profiles.

In a further aspect of the present invention, the profile of each of the wall panel top and bottom edges 42, 44 may be

complimentarily shaped such that the top edge 44a of a first wall panel 24a may be removably attached to the bottom edge 42b of a second wall panel 24b and when joined together, the top and bottom edges create a physical barrier to the passage of water therethrough and wall panels 24a, 24b extend substantially from floor 28 to ceiling 30.

In accordance with another aspect of the present invention, the profile of each of wall panel top edge 44 may include first and second segments 50, 52 which traverse the length of a respective wall panel in adjacent, parallel relationship to each other with first segment 50 extending adjacent to the wall panel outside planar surface 38 and the second segment 52 extending adjacent to the wall panel

inside planar surface 40. The first and second segments 50, 52 may be offset from each other to form a step 54 with the second segment 52 raised relative to the first segment 50 so as to create the physical barrier (see FIGS. 5, 5A, and 6, 6A).

In accordance with another aspect of the present invention, each of first and second wall panels 24a, 24b may include a panel height H which is one-half the length L of support post 22. In this manner, second wall panel 24b may be rotated 180 degrees and flipped edge-over-edge. In such an instance, opposite outside and inside planar surfaces 38b, 40b, top and bottom edges 42b, 44b, and opposite first and second side edges 46b, 48b of side wall panel 24b may be redefined accordingly. Second wall panel 24b may then be joined together with first wall panel 24a as described above.

FIGS. 2 through 7 illustrate a stepwise method of construction of temporary wall structure 26. As shown most clearly in FIG. 2, a first support post 22a may be removably secured to floor 28 and ceiling 30 via respective connectors 50a, 50b. As shown in FIGS. 3 and 4, first modular wall panel 24a may then be received within channel 36. Second modular wall panel 24b may then be coupled to first modular wall panel 24a as described above. A second support post 22b may then couple with wall panels 24a, 24b (such as through a respective groove, not shown) so as to constrain wall panels 24a, 24b between support posts 22a, 22b and prevent lateral displacement of the wall panels. Additional support posts 22c and modular wall panels 24c, 24d may be serially added so as to create continuous temporary wall structure 26.

In accordance with one aspect of the present invention, one or more wall panels 24 may further include a reinforcement member attached to each wall panel. By way of example and by no means limiting solely thereto, as shown in FIGS. 9 and 10, the reinforcement member may a furring channel 56. In a further aspect of the present invention, wall panel 24 may include a panel channel 58 which complimentarily shaped to furring channel 56 so as to permit furring channel 56 to be slidingly and removably attached into panel channel 58 of wall panel 24. Additionally or alternatively, as shown in FIG. 11, the reinforcement member may include a reinforcement material 60 attached to one or both of the inside and outside planar surfaces 38, 40 of each wall panel 24. In accordance with an aspect of the present invention, wall panels 24 may be formed from expanded polystyrene and the reinforcement material may comprise string reinforced polyethylene.

Although the invention has been described with reference to preferred embodiments thereof, it is understood that various modifications may be made thereto without departing from the full spirit and scope of the invention as defined by the claims which follow. While specific reference has been made to rotational movements of device components, it should be understood by those skilled in the art that such rotations may be reversed and that such teachings are within the scope of the present invention.

What is claimed is:

1. A weather resistant temporary wall system, comprising:
  - a) a plurality of wall panels each having an outside planar surface and an inside planar surface and top and bottom edges each having a predetermined edge profile and opposite first and second side edges each having a predetermined side edge profile;
  - b) a plurality of support posts adapted to removably attach and extend between a floor and a ceiling, said support posts each having first and second opposite post side edges each having a predetermined post side edge profile;

wherein said side edge profile of each of said wall panel first and second side edges is formed complimentary to said post side edge profile of each of said support post first and second post side edges such that said wall panels are configured to be removably attached to and between said support posts;

wherein said profile of each of said wall panel top and bottom edges are complimentary shaped to one another such that the top edge of a first wall panel is configured to be removably attached to the bottom edge of a second wall panel, and when joined together the top and bottom edges creating a physical barrier to the passage of water therethrough; and

wherein said profile of each of said wall panel top edges include first and second segments which traverse a length of a respective panel in adjacent, parallel relationship to each other with said first segment extending adjacent to the wall panel outside planar surface and the second segment extending adjacent to the wall panel inside planar surface and wherein said first and second segments are offset from each other to form a step with the second segment raised relative to the first segment, and wherein said wall panel bottom edges include first and second segments which traverse the length of a respective panel in adjacent, parallel relationship to each other with said first segment extending adjacent to the wall panel outside planar surface and the second segment extending adjacent to the wall panel inside planar surface and wherein said first and second segments are offset from each other to form a step with the second segment raised relative to the first segment.

2. The weather resistant temporary wall system of claim 1 and further comprising a reinforcement member attached to each wall panel of said plurality of wall panels.

3. The weather resistant temporary wall system of claim 2 wherein said reinforcement member is a furring channel.

4. The weather resistant temporary wall system of claim 3 wherein each of said plurality of wall panels includes a channel complimentary shaped to said furring channel to permit said furring channel to be slidingly and removably attached into the channel of a respective wall panel.

5. The weather resistant temporary wall system of claim 1 and further comprising a reinforcement material attached to one or both of said inside planar surface and said outside surface of each wall panel of said plurality of wall panels.

6. The weather resistant temporary wall system of claim 5 wherein said reinforcement material comprises string reinforced polyethylene.

7. The weather resistant temporary wall system of claim 1 wherein said wall panels are formed from expanded polystyrene.

8. The weather resistant temporary wall system of claim 7 and further comprising a reinforcement material attached to one or both of said inside and outside surfaces of each wall panel of said plurality of wall panels.

9. The weather resistant temporary wall system of claim 8 wherein said reinforcement material comprises string reinforced polyethylene.

10. A method of forming a weather resistant temporary wall system, comprising the steps of:

a) providing a plurality of wall panels each having an outside planar surface and an inside planar surface and top and bottom edges each having a predetermined edge profile and opposite first and second side edges each having a predetermined side edge profile wherein said profile of each of said wall panel top and bottom

5

edges are complimentary shaped such that the top edge of a first wall panel is configured to be removably attached to the bottom edge of a second wall panel when joined together and wherein said profile of each of said wall panel top edges include first and second segments which traverse a length of a respective panel in adjacent, parallel relationship to each other with said first segment extending adjacent to the wall panel outside planar surface and the second segment extending adjacent to the wall panel inside planar surface and wherein said first and second segments are offset from each other to form a step with the second segment raised relative to the first segment, and wherein said wall panel bottom edges include first and second segments which traverse the length of a respective panel in adjacent, parallel relationship to each other with said first segment extending adjacent to the wall panel outside planar surface and the second segment extending adjacent to the wall panel inside planar surface and wherein said first and second segments are offset from
